C. COLVIN,

FENCEPOST.

APPLICATION FILED JULY 8, 1916.

1,360,501.

Patented Nov. 30, 1920.

INVENTOR
Chase Colvin,

By Edward J. Reed

ATTORNEY.

UNITED STATES PATENT OFFICE.

CHASE COLVIN, OF SOUTH CHARLESTON, OHIO.

FENCEPOST.

1,360,501.

Specification of Letters Patent. Patented Nov. 30, 1920.

Application filed July 8, 1916. Serial No. 108,105.

To all whom it may concern:

Be it known that I, CHASE COLVIN, a citizen of the United States, residing at South Charleston, in the county of Clark and State 5 of Ohio, have invented certain new and useful Improvements in Fenceposts, of which the following is a specification, reference being had therein to the accompanying drawing.

10 This invention relates to fence posts, and the object of the invention is to provide a metal post which can be manufactured from rolled stock with but little labor and at small expense; and to provide such a post 15 which will have ample strength and rigidity but which will have a part, or parts, of such relative thinness that they can be readily punched to form openings for the wire fastening devices.

20 A further object of the invention is to provide such a post which will be so tapered as to form a driving point which will drive straight; and to provide the same with anchoring devices which will resist the tendency 25 of the post to work upward in the ground, but will not interfere materially with the driving of the same. It is also an object of the invention to provide the post with means for supporting a top rail.

30 A further object of the invention is to provide a wire fastening device adapted to coöperate with such a post to quickly and firmly secure the fence wires thereto. Other objects and advantages will appear as the 35 invention is described in detail.

40 In the accompanying drawings Figure 1 is a vertical elevation of a fence post embodying my invention, partly broken away to reduce the length thereof; Fig. 2 is a perspective detail view of the upper end of such a post; Fig. 3 is a transverse sectional view taken on the line $x-x$ of Fig. 1, looking in the direction of the arrows; and Fig. 4 is a detail view of a lower portion of the post 45 showing the anchor formation.

45 In carrying out my invention I form the post from a section of rolled stock which has been so rolled as to provide a relatively thick portion to form what may be termed 50 the body of the post, and a relatively thin portion in which openings may be readily punched to receive the wire fastening devices. Preferably, the stock is T-shaped in cross section and comprises what is commonly known as "T-iron." It is, however, 55 specially rolled so that the central web, or

shank of the T, 1, which may be said to form the body portion of the post, will be relatively thick so as to give the necessary strength and rigidity to the post. The laterally extending flanges, or arms of the T, 60 2, are comparatively thin so that they can be readily punched to form relatively small openings to receive the wire fastening devices. Were the flanges of a thickness equal 65

to the thickness of the central web, or body portion, of the post, it would be necessary in order to punch the same, in practical operation, to form the openings much larger than is necessary to receive the wire fastening device, and, as a result the flange would 70 be materially weakened. The flanges, which extend at right angles to the web, are arranged substantially parallel with the fence wires and form a relatively wide surface 75

against which the wires are clamped by the wire fastening devices. Further, these flanges, though of less thickness and consequently of less strength than the central web, are of ample strength to prevent the 80 movement of the post edgewise of the web, while the web resists the movement of the post edgewise of the flanges. Further, the flanges being formed integral with the web add materially to the strength and rigidity 85

of the post. The openings in the flanges 2 for the wire fastening devices may be arranged in any suitable manner, but they are preferably arranged comparatively close together to permit any desired spacing of the 90 fence wires. Wire fastening devices of various kinds may be used to secure the fence wires to the post, but the shape of the post lends itself particularly to one form of fastening which is very simple and which can 95 be very quickly and easily applied to the post and to the fence wire. This fastening device comprises a short section of wire adapted to be passed through one of the openings in the flanges from that side of 100 the flange adjacent to the web 1 and is provided with suitable means to prevent the same from being drawn entirely through the opening. In that form of the device shown on the lower fence wire in Fig. 1 and 105 in detail in Fig. 3, the fastening device is provided with a hook shaped portion 4 which engages about the edge of the web 1 of the post and thus limits the movement of the fastening device through the opening.

110 That portion of the fastening device which projects beyond the opening is of such

length to enable it to be passed about the fence wire even though the wire may be spaced some little distance from the opening, then by means of a wrapping tool, of 5 any suitable kind, various kinds being known in the art, the end of the fastening device is twisted about the fence wire, as shown at 5. This fastening device being provided with the hook-shaped end formed 10 thereon, it is a very simple matter to insert the end of the device through the opening and cause the hook shaped end to engage the edge of the web, or body of the post. If desired, the fastening device may be provided 15 with a head after the manner of the nail head, as shown in the upper device of Fig. 1, to prevent it from being drawn through the opening in the flange.

Fence posts of this type are commonly 20 driven into the ground and it is desirable that they should be pointed in such a manner that they will drive straight. With various kinds of posts now in use, for instance the angle-iron post, the tapering of 25 the end of the post is necessarily such that the post will draw in driving thus making it very difficult to drive the same straight. In the present post this objection is entirely overcome by tapering the flanges toward the 30 central web thus providing a driving point, or edge, which will drive straight into the ground without any tendency to draw. This taper may be very easily secured by shearing the lower edges of the flanges, as shown at 35 6 in the drawings.

It is also desirable that posts of this character should be provided with anchoring devices of some kind to prevent them working upward out of the ground. The present 40 post is very easily provided with such an anchoring device by providing oblique slits in the flanges and bending the points formed on the flanges, by thus slitting the same, away from the body of the flange so 45 as to form barbs 7, the barbs being preferably formed on opposite sides of each flange. These barbs do not interfere appreciably with the driving of the post but will bite into the ground and very effectively 50 resist any tendency of the post to work upward.

In certain types of fence the posts are connected one to the other at their upper ends by a top rail which, in the case of a metal

fence, is usually in the form of a tube, or 55 pipe. To enable such a top rail to be applied to my T-shaped post, the same may be, if desired, provided with an opening near the upper end thereof to receive the top rail, or pipe, and I have shown the post in the 60 present drawings as provided with such an opening. It will, however, be understood that this opening is not the essential part of the invention and that the post may be provided without the same. It is desirable that 65 the opening, which is shown at 10, in Fig. 2, should be formed in the web close to the flanges in order that the top rail may be so located. It is not practical to form a die 70 which could be so located with reference to the flange as to enable the opening to be punched in the desired position. I have therefore cut away one of the flanges 2, at the upper end of the post, flush with the face of the web 1, as shown at 11, so that 75 the web may be laid flat upon the die during the punching operation.

It will be apparent from the foregoing description that I have provided a post which is not only very simple in construction and inexpensive to manufacture, but has ample strength and rigidity and is of such a character that it can be easily driven into the ground and when so driven will be retained firmly in position. It will further 85 be apparent that the wire fastening devices can be very quickly applied thereto and that the anchoring devices are easily formed on the lower portion thereof.

While I have shown and described one 90 embodiment of my invention I wish it to be understood that I do not desire to be limited to the details of construction as various modifications will occur to a person skilled in the art.

Having now fully described my invention, what I claim as new, and wish to secure by Letters Patent, is:—

A T-shaped fence post having one flange 95 cut away near one end of said post, and having an opening punched in the web of said post close to the surface of the remaining flange and adjacent to the cut-away portion of the first-mentioned flange.

In testimony whereof, I affix my signature 100 hereto.

CHASE COLVIN.
